UNITED STATES PATENT OFFICE.

SPIROS C. MARKATOS, OF NEW YORK, N. Y.

STEAMING APPARATUS.

Application filed June 21, 1927. Serial No. 200,437.

This invention relates to a steaming apparatus and has for its primary object the provision of a construction by means of which hats may be more effectively steamed while permanently out of contact with moisture.

An object of the invention is the novel manner of shaping and constructing the container so as to effectively engage and support within the container a separator that functions to allow dry steam to readily pass for action on the hat that will positively prevent the passage of moisture into contact with the hat.

Another object of the invention is the novel manner of constructing the separator and associating the same with the container so that contacting engagement between the separator and the container will be such that steam will be positively held against escaping in the wrong direction.

Another object of the invention is the design of a separator from porous material such as canvas of a shape to be readily suspended within the container and when in place will divide the interior of the container into a lower steam receiving chamber and an upper steaming chamber, the latter receiving directly the hat to be steamed.

A feature of the invention is the provision of a foraminous metallic plate as a portion of the bottom structure of the separator so that the separator may be effectively secured within the container and further providing the separator with a contractable open end capable of overlapping engagement with the edge of the container so as to not only effectively secure the separator to the container but provides a soft pliable seat for the rim of the hat to be steamed.

Besides the above my invention is distinguished in the novel manner of constructing and designing the separator so that the same may be readily connected to containers of various sizes and shapes without in any manner interfering with the efficient operation thereof.

With these and other objects in view, the invention will be better understood from the following detailed description taken in connection with the accompanying drawings, 50 wherein:

Figure 1 is a vertical sectional view of the steaming apparatus,

Figure 2 is a fragmentary side elevation,

Figure 3 is a sectional view on line 3—3 of Figure 1,

Figure 4 is a sectional view on the line 4—4 of Figure 1,

Figure 5 is a sectional view on the line 5—5 of Figure 1,

Figure 6 is a perspective view of the separator removed from the container.

Figure 7 is a fragmentary sectional view through the foraminous plate,

Figure 8 is a sectional view on the line 8—8 of Figure 6.

Again referring to the drawings, illustrating one of the many constructions of my invention, the numeral 1 designates a container shown in this particular instance as shaped to provide an open neck portion 2 and intermediate bulged portion 3, and a lower contracted portion 4, the latter in turn being shaped to provide a catch basin 5. The open top 6 of the container is surrounded by a bead 7 that extends in the required direction to have a snug interfitting engagement with the novel type of separator hereinafter described.

It will also be noted that the container is provided with an inner annular wall 8 terminating in a shoulder 9 at its juncture with the lower contracted portion 4. To complete the construction of the container I provide a drain pipe 10 in communication with the catch basin 5 so as to properly remove moisture accumulating in the catch basin 5 resulting from the action of the steam issuing from the steam nozzle 11 that is in communication with the feed pipe 12.

A lid 13 hinged to the body of the container as illustrated at 14 is of the required area to properly cover the open end of the container and to rest upon the bead 7 and is further provided with an auxiliary steaming extension 15, and has the basic structural features of the container just described and more particularly the lid construction is

fully set forth and claimed in a co-pending application filed October 21, 1925, Serial Number 64,052. Further detailed consideration of the container will be eliminated.

My improved separator designed for the

purpose of separating the moisture from the steam in the passing of the latter to the hat being steamed, consists primarily of a bag 16 constructed from porous material such as 5 canvas to enable the dry steam to readily pass in its travel towards the hat, but will positively prevent the passage of moisture thereby preventing moisture from coming into contact with the hat. The bottom 17 of the 10 bag has attached thereto a rigid foraminous plate 18 preferably constructed from metal to reduce the manufacturing cost thereof and this plate is of the required area to snugly co-act with the material of the bag to provide 15 a close sliding contact with the wall 8, to prevent the passage of steam therearound.

As far as I have proceeded, it will be appreciated that the formation of the bottom portion of the bag is such that the container 20 is subdivided into a lower steam receiving chamber 19 and a steaming chamber 20 so that steam in passing from the chamber 19 to chamber 20 must pass through the porous material of the bag and through openings in 25 the plate, thereby completely and efficiently separating the moisture from the steam before it enters the steaming chamber to perform the steaming operation. There are various manners in which the bottom portion 30 of the separator can be anchored in place but for the purpose of illustration, I have shown a stud 21 projecting upwardly from the nozzle 11 and arranged in an opening 22 in the bottom structure of the bag so that upon 35 turning of the nut 23 the bottom structure is effectively secured in place. The flexibility of the bag 16 enables the same to readily accommodate itself to containers of various shapes and for the purpose of effectively suspending the bag within the container, I have 40 provided the former with fastening means illustrated in the particular case as a hem 24 receiving a draw string 25 for contracting the open end portion 26 of the bag around the 45 bead 7 as clearly shown in Figure 1. This engaging connection between the bag and bead 7 provides a flexible covering for the bead and assures the complete absorption of any condensed moisture, thereby fully protecting the hat against being damaged by 50 water accumulations.

As heretofore stated the bottom structure of the bag engaging the wall 8 to prevent the escaping of steam through the space between 55 the outer surface of the bag and the inner wall of the container, but for the purpose of positively assuring such a result, and to assure the extending of the bag to its full capacity, I have provided a split band or retainer 27 so arranged that in the expanding action thereof the bag will be drawn into snug engagement with the interior wall of the container.

Arranged between a cover strip 28 and the 60 body of the bag is an absorption pad 29 snug-

ly arranged contiguous to the open end of the container so as to be placed in a most favorable position relative to the hat being steamed so as to cooperate in the absorption of moisture that tends to accumulate at the top portion of the container. The stitchings 30 effectively secure the pad in place and materially reinforce the separator at the open end thereof. 70

From the foregoing description, taken in 75 connection with the accompanying drawings, it will be appreciated that I have in a very novel manner so designed a container and a separator that the two will cooperate in an efficient manner to positively separate moisture from steam, as produced by condensation previous to the entrance of the steam into the bag and as produced by condensation after entrance into the bag, facilitated by the arrangement of the upper portion of the bag 80 around the edge of the container, thereby preventing moisture from coming into direct contact with the hat. It will also be appreciated that the novel manner of designing and construction the various parts of the invention 85 enables the apparatus to be manufactured at a relatively low cost and besides enables the separator to be easily positioned and adjusted in place. 90

It is of course, to be understood that the 95 separator may be constructed from various materials and may be designed in various other manners than illustrated and may be associated with the container in various other ways and besides the container may be mechanically constructed to function with the separator in various other arrangements than illustrated, and, therefore, I do not desire to be limited in protection in any manner whatsoever except as set forth in the following 100 claims. 105

What I claim is:

1. In combination with a steam container a closed bottom bag arranged within the container for subdividing the same and contacting with the interior wall of the container at spaced points, for the purpose set forth. 110

2. In combination with a steam container having an open top surrounded by a bead, a separator of bag-shaped formation arranged within the container for subdividing the same and having a detachable overlapping engagement with said bead for controlling the position of the separator within the container and means for establishing contact between spaced portions of the separator and the interior wall of the container. 115 120

3. In combination with a steam container having an open top and a threaded stud at the bottom thereof, a bag suspended within the container for subdividing the latter and including a foraminous bottom plate detachably secured to said stud. 125

4. A separator for steam chambers comprising a porous bag and a foraminous metal- 130

lic plate attached to the bottom of the bag and a split band attached to an intermediate portion of the bag for extending the same into contact with an article in which the bag is arranged.

5. A steam and moisture separator comprising a porous bag having an open end provided with a hem, a draw string arranged in

the hem, a strip of absorbing material surrounding a portion of the bag, a split band 10 secured to an intermediate portion, of the bag and a foraminous metal plate secured to the bottom of the bag.

In testimony whereof I affix my signature.

SPIROS C. MARKATOS.
